UNITED STATES PATENT OFFICE.

PAUL LÉCULIER, OF LYONS, FRANCE.

APPARATUS FOR DRYING FABRICS OR THE LIKE.

Application filed February 5, 1924. Serial No. 690,857.

To all whom it may concern:

Be it known that I, PAUL LÉCULIER, residing at Lyons, Rhone, France, a citizen of the French Republic, have invented a certain new and useful Apparatus for Drying Fabrics or the like, of which the following is a specification.

Drying of dressed or other fabrics is ordinarily effected by means of a movable frame-work carrying a fire of wood charcoal gas or the like or the fire is fixed and the fabric is movable.

In both cases the fire is arranged below the fabric to be dried.

15 The residues of combustion arising from these different methods of heating are all more or less harmful to the workers.

Further the soot and the dust produced by these fires rapidly soil the workrooms and 20 the material and are the cause of numerous stains on the fabrics manipulated and possibly also sparks may be projected on to the fabric and burn it.

The present invention has for its object a 25 method and an apparatus for electrically drying fabrics.

This method consists in placing the source 30 of heat either above or below the fabric and bringing it as close as possible thereto to lessen the loss of heat by radiation and to prevent an exaggerated use of current.

The apparatus comprises a frame carrying 35 a number of parabolic reflectors in the focus of each of which is placed a heating element.

These reflectors are juxtaposed and fixed 40 to rods, chains or to any other device allowing them to play so they do not become deformed under the action of expansion caused by the heat.

45 The best division of the calorific density is obtained by arranging the reflectors staggered parallel to themselves and slightly inclined in the direction of displacement of the apparatus or of the fabric. The temperature of a heating body is not in effect uniform over all its length but decreases from its centre to its points of support. Further it is preferable to adopt this arrangement which allows of submitting any 50 part of the fabric successively to the entire range of temperature of the heating body.

The apparatus provides for absolute cleanliness and does not give off smell or harmful gas, soot or the like. Its stopping and its 55 starting only necessitates the simple operation of a switch or a combiner when it is de-

sired to regulate the temperature by the suppression or the addition of one or several elements or by variation of the pressure.

It can equally be utilized for drying dressed or other fabrics arranged or not on tenters which may be fixed or actuated mechanically by endless chain gear.

Finally among other advantages it can be placed above existing tenters without incorporating any other modifications than the addition of a trackway and it can be placed at a distance from the fabric, much less than a coke or charcoal heater.

When the apparatus is placed below a movable endless carrier or below the moving material it is mounted on a mechanically operated device which displaces it vertically to move it further from or nearer to the fabric. The same device can also be employed when the apparatus is above the fabric by simply modifying the arrangement and the length of the articulations and of the guides.

When the apparatus is placed above the fixed or movable fabric its vertical support can be made in two parts adapted to slide on one another so as to allow of regulating the distance of the heat reflectors therefrom also the height of the individual reflectors can be regulated by means of their suspension chains.

The heating elements can be easily replaced by others and the reflectors are interchangeable. The reflectors are of definite shape; they are closed at each end by a cheek provided with a support for the heating body mounted in a refractory and insulating tube.

The annexed drawings illustrate the invention.

Fig. 1 is a side view in elevation of a simple form of movable drying apparatus or heater.

Fig. 2 is a view in elevation thereof with partial section on line 2—2 of Fig. 3.

Fig. 3 is a plan view of Fig. 2 with partial removal of the upper plate and of a reflector.

Figs. 4 and 5 show respectively in elevation and in plan a fixed heater in which the heating elements are staggered the fabric being carried on an endless chain conveyor.

Fig. 6 is a perspective view of a modified form of movable heater, the fabric being mounted on a fixed support.

Fig. 7 is a section on line 7—7 of Fig. 8 of a reflector.

Fig. 8 is a cross section thereof on line 8—8 of Fig. 7 and

Fig. 9 is an end view.

Fig. 10 is a perspective view showing an 5 automatic heater adapted to travel on a printing table.

Referring to Figs. 1 to 3 *a* indicates the frame support.

10 *b* shows parabolic reflectors of polished metal or refractory material of any kind suspended from the frame *a* by bars *c*.

15 *d* indicates the heating elements. *e* are grooves in which pivots of the suspension rods of the end reflectors can slide so that they can be given a tilted position. *f* are rails on which the rollers *g*, fixed by brackets *h* to the frame *a* can roll. This track-way comprising two rails could be replaced by a suitable mono-rail device.

20 *k* indicates slots in the walls of the reflectors to allow the free passage of the fixing devices for the heating elements.

Referring to Figs. 4 and 5 in which the reflectors and heating elements are staggered.

The reflectors *b* rest on the frame *a* by means of small supports *l* fixed to the piece *m* which connects two consecutive reflectors.

25 The inclination of the heating bodies *d* in the axis of displacement of the fabric *n* can vary, but an inclination of from 22°, 30° gives excellent results with filaments of 36 c. length. As shown in Fig. 5 the head of the filament *d* is in the direction of travel of the filament on the same line as the middle of the filament *d*.

The heater can be vertically displaced by the following means:—

30 Under the frame *a* two grooved rollers *o* are mounted which roll on guides *p* placed on each side of the heater and of variable number according to its importance. There are also provided articulated means comprising in particular crank arms *q* and *r* connected respectively to shafts *s* and *t*. On these shafts toothed wheels *u* and *v* connected by a chain *w* are fixed. The movement is governed by means of the actuating lever *x* keyed on the shaft *t*. A rack device *y* or similar device allows of arresting the heater at any position, the movable means for which is balanced by a weight *z* fixed to the shaft *s*.

35 Pins arranged in the rack *y* allow of limiting the displacements particularly in height of the heater the extreme positions of which are shown in Fig. 4.

In the construction shown in Fig. 6 the reflectors are also staggered and in this construction the reflectors are connected together by small pieces *m* similarly to the fixed heater but in this case they are suspended from the frame *a* by means of small chains *s*, the links of which allow their 65 length to be regulated. The height of the

heater above the fixed fabric carrier *4* can be further regulated by sliding the suspension bars *5* in the V irons *6* after having withdrawn the bolts *7*.

This construction is also provided with 70 means for moving the heater *a*, said means comprising a bar *8* articulated at *9*, an emplacement for housing the current switch *10*, a trolley *11* for taking the current and further the rollers *g* are mounted on a support with a vertical shaft *12* in order to allow the heater to travel without difficulty over small radius curves of the rails *f* serving to pass from one track to another.

A reflector is illustrated in Figs. 7 to 9 80 the parabolic curve of which is such as to produce uniform radiation of the heat rays from the heating body *d*. The contact members which support the latter transverse the ends *13* of the reflector *b* through a porcelain or other refractory and insulatory sleeve *14* which rests in a reversible support *15* hooking on the rods of its fixing bolts *16*.

The displacement of a movable heater either above or below the fabric to be dried 90 can be effected in various ways.

The heater can be connected to a cable tractor operated by a motor or by hand.

It could also be put in movement by a 95 small electric motor carried by the carriage, the said motor actuating one or more driving wheels rolling on rails or gearing with a rack.

This form of construction is shown in 100 Fig. 10. The reflectors *b*, arranged staggered, are suspended to the frame *a* of the heater which rests on the frame *17* of the carriage which runs on rails *19* provided with a rack *20* on each side of the table *18* and in engagement with toothed pinions driven by a motor *21* either directly or by means of reducing gear enclosed in a casing *22*.

23 is a button for unclutching the motor and 24 a crank operated by hand.

The switches 25 on the upper part of the heater are for switching off the elements not required when the fabric is narrower than the width of the table or when by reason of its lightness the pattern is obtained by depositing very little colour on the fabric which dries quickly without the necessity of using all the heating elements.

The current is conveyed by two contact rails arranged on the side of the table *18*. The heater may be drawn along by any suitable means and in particular by any printing apparatus movable over a table as used in printing on fabrics and the like, it could also be moved by hand.

The method of introducing the current for a movable radiator is not shown on the drawing but any of the known devices such as friction contacts, supple cables, current conveying rails or the like may be adopted.

The device could equally be utilized for drying printed papers and fabrics of all kinds.

What I claim as my invention and desire to secure by Letters Patent of the United States is:—

1. Apparatus for drying fabrics comprising a frame, means for supporting said frame, a series of oblong parabolic reflectors within said frame means for suspending said reflectors from said frame, electrically heated elements in said reflectors and means for conveying electric current to said heating elements.
- 15 2. Apparatus for drying fabrics comprising a frame, means for supporting said frame means for vertically adjusting said frame, means for securing said frame in the vertically adjusted position, a series of oblong parabolic reflectors within said frame means for suspending said reflectors from said frame, electrically heated elements in said reflectors and means for conveying electric current to said heating elements.
- 20 3. Apparatus for drying fabrics comprising a rectangular frame means for support-

ing said frame a series of parabolic reflectors of rectangular shape arranged in staggered formation within said frame and having their edges parallel to one another but diagonally to said frame, means for suspending said reflectors in said frame, means for adjusting the depth of dependence of individual reflectors from said frame electrically heated elements in said reflectors and means for conveying electric current to said heating elements.

4. Apparatus for drying fabrics comprising a frame, a carriage means on which the wheels of said carriage roll, framing connecting said frame to said carriage, a series of juxtaposed oblong reflectors supported by said frame means for adjusting the position of said reflectors in said frame interchangeable electrically heated elements in said reflectors, means for conveying electric current to said heating elements and means for imparting horizontal movement to said carriage and thereby said frame.

In witness whereof I have signed this specification.

PAUL LÉCULIER.
